UNITED STATES PATENT OFFICE.

JOHN F. SCOTT, OF INDIANAPOLIS, INDIANA.

EYE-SHIELD DIFFUSER.

1,216,855.

Specification of Letters Patent. Patented Feb. 20, 1917.

Application filed March 22, 1915. Serial No. 16,041.

To all whom it may concern:

Be it known that I, JOHN F. SCOTT, a citizen of the United States, residing at Indianapolis, in the county of Marion and 5 State of Indiana, have invented a new and useful Eye-Shield Diffuser, of which the following is a specification.

The necessity for shading the eye from the direct rays of electric lights is being more 10 and more recognized, and has been rendered much more imperative by the development of the modern high efficiency incandescent lamps. The high intensive brilliancy of the light from the modern incandescent lamp, 15 and particularly of the light from the recently developed nitrogen lamp, is objectionable, and even dangerous, to the eye; in addition, the distribution of light from these nitrogen lamps is not uniform, so that a 20 streaked illumination is produced by the direct rays therefrom.

It is the object of my present invention to provide a simple form of eye shield, and preferably a diffuser, for the electric incandescent lamp, and especially for the modern high brilliancy lamps, although the device is not limited to these lamps; and to make this device readily applicable to all 25 the standard forms of lamps so that it can be applied inexpensively to existing installations.

In carrying out my invention, I provide a holder which can be mounted on the lamp bulb itself, preferably at the base thereof, 30 and from this holder suspend an inverted dome-shaped member which extends around the lower and larger end of the lamp bulb and intercepts the direct rays of light from the lamp. Preferably, this inverted dome-shaped member is of translucent glass, so 35 that it acts at once to diffuse the rays of light from the lamp and permit their passage in a diffused condition, and as a reflector for producing an upward illumination 40 which can be reflected downward by a suitable reflector for indirect or semi-indirect 45 lighting. However, the inverted dome-shaped member may be wholly opaque, in which case the diffused transmitted light is 50 eliminated entirely and the lighting is wholly indirect.

The single figure of the accompanying drawing is a perspective view of a lamp equipped with my eye shield diffuser, also 5 showing in dotted lines the lamp socket and one form of reflector.

The incandescent electric lamp 10 is shown as of the modern nitrogen type, having the usual base 11 which is provided with a threaded portion 12 for fitting into the standard socket 13. If desired, any suitable reflector 14 may be mounted above the lamp, as on the socket 13.

A holder 15 is mounted on the base 11 of the lamp 10. This holder comprises a suitable portion for surrounding, and clamping itself upon, the base 11, this clamping portion being shown as a helix 16 of spring wire, the ends of this helix projecting therefrom and being bent downward to form supporting fingers 17, the lower ends 18 of which are bent outwardly. The fingers 17 extend obliquely, substantially parallel to the wall of the lamp bulb 10. The fingers 18 extend through diametrically opposite holes 19 in an inverted dome-shaped member 20, which is thereby hung from the holder 15. This dome-shaped member extends around the lower end of the lamp bulb 10, being spaced therefrom, and intercepts the downward rays of light therefrom and also any sideward rays below the horizontal. Preferably this inverted dome-shaped member 20 is made of a translucent glass, which permits the passage of the rays of light 25 from the lamp 10 but diffuses and modifies them to make the distribution of light more uniform and preferably to eliminate the rays of higher frequency, such as the injurious ultra-violet rays. Glass which will 30 do this is now known. Preferably the inner surface of the inverted dome-shaped member is a polished surface so that there is a considerable reflection of light upward 35 toward the reflector 14, which in turn reflects 40 the light downward to produce indirect lighting. If desired, the inverted dome-shaped member 20 may be opaque instead of translucent, thus producing a wholly indirect 45 lighting; but at present I prefer to make 50 such member translucent, so that the resultant lighting is semi-indirect.

This eye shield diffuser and its holder may be applied to any standard lamp, by simply fixing the clamping parts 16 of the 55 holder 15 on the base 11 of the lamp, and bringing the fingers 17 inward so that the bent tips thereof register with the holes 19, and then allowing such fingers to spring outward so that the bent lower ends 18 may 60 pass through the holes 19 and thus support the eye shield diffuser 20.

I claim as my invention:

1. An eye shield diffuser, comprising a support having a clamping portion for mounting on the base of an electric incandescent bulb and one or more downwardly projecting portions, said mounting being separate from the lamp socket, and an inverted dome-shaped member of translucent glass hung free from the lower ends of said downwardly projecting portion or portions and inclosing the lower end of the lamp bulb upon which said holder is mounted.
- 10 2. An eye shield diffuser, comprising a support having a clamping portion for mounting on an electric incandescent bulb and one or more downwardly projecting portions, said mounting being separate from the lamp socket, and an inverted dome-shaped member of translucent glass hung free by points at its upper edge or rim from the lower ends of said downwardly projecting portion or portions and inclosing but being spaced from the lower end of the lamp bulb upon which said holder is mounted.
- 20 3. An eye shield, comprising a support having a clamping portion for mounting on the base of an electric incandescent bulb and one or more downwardly projecting portions, said mounting being separate from the lamp socket, and an inverted dome-shaped member hung free from the lower ends of said downwardly projecting portion or portions and inclosing the lower end of the lamp bulb upon which said holder is mounted.
- 30 4. An eye shield, comprising a support having a clamping portion for mounting on an electric incandescent bulb and one or more downwardly projecting portions, said mounting being separate from the lamp socket, and an inverted dome-shaped member hung free by points around its upper edge or rim.

socket, and an inverted dome-shaped member hung free by points at its upper edge or rim from the lower ends of said downwardly projecting portion or portions and inclosing but being spaced from the lower end of the lamp bulb upon which said holder is mounted.

5. An eye shield diffuser, comprising a wire holder having a helical coil portion for fitting upon the base of an incandescent lamp and a pair of downwardly projecting fingers with bent ends, and an inverted dome-shaped member of translucent material having holes for receiving the bent ends of said fingers, said dome-shaped member surrounding the lower end of the lamp bulb upon which said holder is mounted.

6. An eye shield, comprising a holder provided with means for mounting it upon an electric lamp bulb and two substantially opposite arms, and a dome-shaped member hung by substantially opposite points at its upper edge or rim from said two arms and inclosing the lower end of the lamp bulb upon which said holder is mounted, said dome-shaped member having a reflecting interior surface.

7. An eye shield diffuser, comprising a support having a clamping portion for mounting on the base of an electric incandescent bulb and one or more downwardly projecting portions, said mounting being separate from the lamp socket, and an inverted dome-shaped member of translucent glass hung free by points around its upper edge or rim.

In witness whereof, I have hereunto set my hand at Indianapolis, Indiana, this twentieth day of March, A. D. one thousand nine hundred and fifteen.

JOHN F. SCOTT.
